FLEXIBLE TUBE PUMP

Lyndus E. Harper, Kansas City, Mo.

Application December 31, 1943, Serial No. 516,399

16 Claims. (Cl. 103—148)

1

My invention relates to pumps, and more particularly to a flexible tube pump.

It is a purpose of my invention to provide a pump that comprises a flexible walled pump chamber, with which is associated a flexible walled inlet valve and a flexible walled outlet valve, and means for compressing or squeezing the walls of said valves and said pump chamber to obtain a movement of fluid from an inlet connection to a discharge connection. Preferably, said flexible walled valve means and pump chamber are all incorporated in a single flexible walled tubular member. Said flexible walled tubular member is made of resilient material, such as rubber, or the synthetic equivalent thereof, or any similar tubular member that will have the quality of a thick walled rubber tube of returning to its original contour after having been deformed.

It is a particular purpose of my invention to provide a device of the above mentioned character, in which the means for squeezing or compressing the tubular member to seal off portions thereof to provide inlet and outlet valve means and for varying the capacity of a portion thereof to produce a pumping action, has a simple compressing action on the tubular member by a movement transversely of the length thereof, without any longitudinal component to such movement, to thus overcome objections to pumping devices which have been previously provided, that utilize flexible tubular members to obtain a pumping action, in which means for squeezing the walls of the tube together have a movement lengthwise of the tubular member, always in the same direction, which tends to cause the tubular member to be stretched and the material thereof to flow in the direction of movement of said squeezing means, thus causing said material to bunch up at a certain point, and reducing the thickness of the wall of the tubular member at all other points to thus shorten the life thereof.

The above referred to purpose of my invention is accomplished, preferably, by means of followers, which cooperate with cam means to move in a direction transversely of the length of or substantially transversely of the length of the tubular member to bring about the pumping action through operation of the valve means and the pumping means thus provided. Said cam means may constitute a cam for each of said followers or a single cam for all of the followers.

It is a purpose of my invention to provide a pump of the above mentioned character having a body portion that has a passage therein, within

2

which the flexible tubular member having the resilient walls is confined, and to make the passage of such cross sectional size and shape that the same will accommodate the tube when it is squeezed or distorted out of the substantially circular cross sectional contour.

It is another purpose of my invention to provide a pump of the above mentioned character that can be adjusted so as to pump any desired quantity of fluid in a given period of time that it may be desired to pump therethrough, this being accomplished by either varying the speed of rotation of the cam or drive shaft, or by providing means for limiting the movement of the follower or tube compressing member that varies the capacity of the pumping chamber.

An important feature of the invention is that it can be used to introduce material to the suction side of a larger pump and material will not flow through the pump forming the subject matter of this invention, due to the suction created by the larger pump. Similarly, the pump can be used to introduce materials into any line in which there is a partial vacuum or suction and at no time will there be any more material pass through the pump forming the subject matter of this invention than the same is intended to pump in accordance with the adjustment thereof. The pump can be operated either at a very slow rate or at a high rate of speed, as may be found desirable, and can be made with the tubular member of very small bore and also of large bore so that pumps of either small or large capacity, or in face of any capacity, can be built in accordance with my invention.

My pump is particularly adapted for supplying small quantities of fluid material, such as liquid, to larger bodies of liquid, and can be utilized, for example, for introducing small quantities of water purifying or similar material into a larger supply of water in the exact proportion desired, by providing a water meter in the pipe through which flows the water to which the treating or dosing material is to be supplied, and driving my improved pump directly from the drive shaft of the water meter to thus maintain the proportion of purifying material to the quantity of water passing through the meter in accordance with the adjustment of the pump.

Other objects and advantages of my invention will appear as the description of the drawings proceeds. I desire to have it understood, however, that I do not intend to limit myself to the particular details shown or described, except as defined in the claims.

In the drawings:

Fig. 1 is a transverse sectional view through my improved pump, the drive shaft being broken away.

Fig. 2 is a section taken on the line 2—2 of Fig. 1.

Fig. 3 is a section taken on the line 3—3 of Fig. 1.

Fig. 4 is a section taken on the line 4—4 of Fig. 1.

Fig. 5 is a top plan view of a modified form of pump, the cover plate being removed.

Fig. 6 is a transverse sectional view of the pump shown in Fig. 5, the section being taken on a plane corresponding to the line 6—6 of Fig. 5, but the cover plate being shown in position, and

Fig. 7 is a fragmentary sectional view taken on the line 7—7 of Fig. 5, but showing the cover plate in place.

Referring in detail to the drawings, in the form of the invention shown in Figs. 1 to 4, inclusive, the pump comprises a body portion 7, which is shown as being made of two similar halves 8 and 9, which are secured together in any desired manner so as to be held in relatively fixed position. The two halves of said body portion are provided with channels or grooves therein to form a passage 10 therethrough, which is somewhat deeper than it is wide, as shown in the drawings, the width of the passage 10 being substantially that of a flexible tubular member 11, which is, preferably, made of resilient material, such as rubber, or a synthetic material of a similar character to rubber, or any similar material that has sufficient elasticity to return to its original shape after having been distorted out of such shape by applying pressure thereto. The channel 10 is, preferably, provided with an annular groove 12 and an annular groove 13 in the wall thereof, in which the annular ribs 14 and 15 of the inlet connection 16 and outlet connection 17, respectively, are mounted. The inlet connection and outlet connection have reduced end portions 18 and 19, respectively, received within the tubular member 11, and to which the tubular member 11 is clamped by the cooperating halves 8 and 9 of the body portion, which have the channels therein so shaped as to provide a substantially cylindrical or circular portion at 20 and 21 of such diameter as to clamp the end portions of the tubular member 11 between the reduced ends 18 and 19 of the inlet and outlet connections and the wall portions 20 and 21 to provide a liquid tight fit between said inlet and outlet connections and said tubular member 11. The main portion of the channel from the inner end of the inlet connection to the inner end of the outlet connection is, however, preferably rectangular or oblong in cross section, as will be obvious from Figs. 3 and 4.

Said body portion made up of the members 8 and 9 is also provided with suitable channels to provide a passage for the drive shaft or cam shaft 22, and recesses for accommodating the cams provided on said shaft. Said portions 8 and 9 of the pump body may be provided with channels therein to provide the bearing portions 23, 24, 25 and 26 for said shaft, or if desired, separate bearings for the shaft can be mounted in recesses, provided in said members to accommodate said separate bearings, and secured to one thereof. The body portion is further provided with suitable channels in the halves 8 and 9 thereof to provide passages 27, 28 and 29, which serve as guides for reciprocable followers to be

described below. The body portions 8 and 9 may be made of any suitable material, such as metal or plastic material, and if made of plastic material may be molded with the proper passages therein for accommodating the tubular member 11, the shaft 22, the cams on the shaft 22 and the followers.

The shaft 22 is provided with a cam 30, which engages a follower 31, a cam 32 that engages a follower 33, and a cam 34 that engages a follower 35. The body of the pump made up of the portions 8 and 9 is provided with suitable recesses therein to accommodate the cams 30, 32 and 34, these recesses being designated by the numerals 36, 37 and 38, respectively. The cam 30 is provided with a high portion 39, the cam 32 with a high portion 40 and the cam 34 with a high portion 41.

When the high portion of the cam 39 is in engagement with the follower 31 the tubular member 11 is compressed between the end 42 of said follower 31 in engagement therewith and the wall of the passage so that the same will be squeezed or distorted to seal the passage 43 normally existing in said tubular member 11, the passage being closed then, as indicated at 43' in Fig. 2. The portion of the tubular member engaged by the follower 31 in cooperation with said follower 31 and the cam 30 constitutes inlet valve means for the pump and in the position of the parts shown, the suction or inlet stroke of the pump has been completed and the discharge stroke of the pump is about to begin. The high portion 39 of the cam 30 is so related to the high portion 40 of the cam 32 and these high portions are of such relative arcuate length that the movement of the follower 33, which compresses the reciprocable pumping member toward the wall of the passage 10 opposite the end 40 of said follower in engagement with said tubular member 11, does not commence until the follower 31 has reached the position shown in Fig. 2.

Similarly, the high portion 41 of the cam 34 is of such arcuate length relative to the high portion 39 of the cam 30 and the high portion 40 of the cam 32, that the follower 35 will be in engagement with the low portion of the cam 34 at the time that the movement of the follower 33 in a direction to compress the tubular member 11 begins, said follower 35 in cooperation with the portion of the tubular member 11 engaged thereby constituting the discharge or outlet valve of the pump, which will then be wide open to permit discharge of the fluid in the pump chamber formed by the portion of the tubular member 11 opposite the follower 33 to pass out through the same into the discharge or outlet connection 17. Said high portion 41 of the cam 34 is further of such arcuate length and so disposed relative to the high portion 40 of the cam 32 that the same will move the follower 35 so as to compress the tubular member 11 between the end 45 thereof engaging said tubular member 11 and the wall of the passage 10 opposite thereto, to close the passage 43 in the manner illustrated in Fig. 2, after the follower 33 has completed its movement toward the wall of the passage 10 opposite thereto and while the high portion 40 of said cam 32 is in engagement with said follower. Further the high portion 39 of the cam 30 is of such arcuate length and so disposed that it will pass from engagement with the follower 31 and said follower will be in engagement with the low portion of said cam before said high portion 40 of the cam 32 leaves the follower

33, the inlet valve thus opening before the follower 33 begins its return stroke, which constitutes the suction or intake stroke of the pump. The inherent resiliency of the tubular member 11 will cause the followers to remain in contact with the cam surfaces as the low portions of the cams come into engagement with said followers. The pumping rate of said pump can be determined by the rate of rotation of the shaft 22 and any suitable means can be provided for controlling the rate of rotation of said shaft. In addition to this, or instead of this, means can be provided for controlling the amount of material pumped per stroke of the pump by suitable stroke adjusting means to be described below.

Preferably, said stroke adjusting means comprises adjustable stop means for limiting return movement of the follower 33, as in that manner the stroke of the pump and the quantity of material pumped on each stroke can be controlled, as obviously if the follower 33 does not return to the position shown in Figs. 1 and 3, the capacity of the portion of the passage 43 constituting the pump chamber of variable capacity by means of said follower 33 will not be at its maximum. While the follower 33 will compress or squeeze the tubular member 11 against the wall of the passage 10 so as to close the same throughout the length thereof opposite the face 44 of said follower 33, or distorted to substantially the shape of said tubular member shown in Fig. 2, when the limit of the stroke of the follower 33, due to engagement with the high portion of the cam is reached, the amount of material pumped by such action of the follower will be dependent upon the size to which the passage 43 is permitted to expand when the follower moves away from the wall of the passage 10 due to the high portion 40 of the cam leaving the same. While the adjustable stop means for limiting this return movement, and thus the capacity of the pump chamber, may be of any desired character, and may be provided with any suitable means for indicating the adjustment thereof, a simple form of such stop means may be such as shown in Fig. 3, in which an adjustable stop screw 46 is screw-threadedly mounted in the upper member 9 of the body portion 7, the head portion 47 thereof being mounted in a recess 48 therein. Rotation of the screw 46 in the proper direction to the desired extent will, of course, place the end 49 thereof in such position as to stop the follower 33 by engagement therewith at the desired point to limit the stroke thereof to get the desired pumping capacity.

While the tubular member 11 is, preferably, made of rubber or similar material, any suitable material that is flexible, which can be readily distorted so as to seal the passage therethrough at the points at which the followers 31 and 35 engage therewith, and which can in a similar manner be distorted to pump liquid material therethrough by means of the follower 33, can be utilized as long as said material has an inherent resiliency or elasticity, such that it will tend to return to its normal shape of circular cross section, or any other desired cross section in which the passage through the same has its maximum capacity, upon the squeezing pressure exerted thereon by the followers being relieved.

Instead of providing a pump with a straight passage through the same for the tubular member and a plurality of cams for operating the followers to accomplish the pumping action, my improved pump can be made in the form shown

in Figs. 5, 6 and 7, in which the main body portion 50 of the pump is provided with a bearing 51 for the shaft 52, upon which a single cam 53 is mounted. Said body portion 50 is provided with a passage 54 therein, having straight portions 57, 58 and 59 that are substantially rectangular in cross section and, preferably, of greater depth than width, the width thereof being substantially that of the external diameter of the tubular member 55, which is similar to the tubular member 11, previously described. Said passage 54 has curved portions 56 connecting the straight passage portion 58 with the straight portions 57 and 59. The curved portions 56 of said passage are circular in cross section and, preferably, closely fit the tube 55, as shown in Fig. 7. The body portion 50 also has passages 60 and 61 therein, which extend substantially transversely to the straight portions 57 and 59 of the passage 54, which these intersect, and these extend substantially radially from the axis of the shaft 52.

A recess 62 is provided in the body portion 50, sufficiently large to readily accommodate the cam 53 and the passages 60 and 61 extend from said recess to the passage 54. A wide rectangular recess 63 is connected with the recess 62 by a wide passage 64. The cam has a single semi-circular high portion 65 and a semi-elliptical low portion 66, said high and low portions being so related to the followers 67, 69 and 68 slidably mounted in the passages 60 and 61 and in the recess 63 that said followers will operate in proper sequence to compress or squeeze the tubular member 55 into engagement with the wall of the straight portion 57 of the passage 54 to close the inlet valve formed by means of the follower 67 and the cooperating portion of the tubular member 55 before the follower 68 begins to compress or squeeze the tubular member 55, and to retract the follower 69 so as to open the outlet valve formed by said follower and the cooperating portion of the tubular member 55 before said squeezing or compressing action of the follower 68 commences, and conversely to close the outlet valve by means of the follower 69 and open the inlet valve by means of the follower 67 before the return stroke of the follower 68 commences, due to the high portion 65 of the cam disengaging the roller 70 on the follower 68.

Suitable means is provided for adjusting the stroke of the follower 68 to any desired length to pump the desired quantity of fluid material per stroke of said follower. The follower 68 is, preferably, provided with a partially cylindrical recess 71 in which the roller 70 is seated. Said roller is mounted on a depending shaft-like or pivot portion 72 of a slide 73 mounted for reciprocation in a passage 74 in the cover member 65 fixed to the body portion 50 to complete the pump body. Said cover member is also provided with a recess 76 to accommodate the depending member 72 in its movements with the follower 68. The slide 73 has a depending bracket portion 77 provided with a threaded opening for receiving the adjustable stop screw 78 having a knurled head 79 thereon for adjusting the same. The screw 78 also has a nut-like locking member 80 thereon having a finger piece thereon for adjusting the same. Said screw can be adjusted to limit the return movement of the follower 68, said screw thus serving as adjustable stop means for the follower.

Any suitable means may be provided for driving the shaft 52, but, preferably, means is pro-

vided the speed of which is adjustable. One of the desirable applications of a pump of the character shown in Fig. 5 is to supply small quantities of dosing material, such as water purifying material, to a larger quantity of liquid in proper proportion, such as to water for softening or purifying the same, and in such case it is highly desirable to operate the shaft 52 at speeds in proportion to the amount of water that is to be treated. This can be readily accomplished by connecting the shaft 52 with the shaft 81 of a water meter 82 by means of any suitable means, such as the cross bar 83 which is mounted on the shaft 81 to rotate therewith, and has pins 84 projecting upwardly therefrom, one of which engages the arm 85 provided on the shaft 52, when the body portion 50 is placed in position on the meter 82. The body portion 50 is provided with a flange 86, which seats on the water meter and is bolted thereto by means of the bolts 87, said body portion having a slight offset therein at 88 to seat in the ledge usually provided for the removable top of the water meter.

Screw-threaded openings 89 may be provided in the body portion 50 for fastening said body portion to any suitable base or bracket, or other means for mounting the same by means of screw-threaded headed members of any suitable character. Said pumping means can be made of such small size that the same can be readily driven by a water meter proportionate to the rate of rotation of said meter, and thus proportionate to the rate at which the water passes through a conduit or pipe in which the meter is interposed, without in any manner interfering with the operation of the water meter. Preferably the tubular member 55 passes from the passage 54 out of the pump body through enlarged end portions 90 of said passage, provided to clamp spiral stiffening members 91 between said tubular member 55 and the walls thereof to hold said stiffening members in position to prevent any kinking of said flexible tubular member 55 where it passes from the pump body.

It will be noted that in both forms of the invention the ends of the followers are provided with rounded contours so as to avoid sharp corners that might cut or sharply bend or crease the resilient deformable tube to avoid injury thereto.

What I claim is:

1. In a pump of the character described, a flexible tubular member, an inlet conduit leading into one end thereof, a discharge conduit leading from the other end thereof, reciprocable means for sealing off a portion of said tubular member from said inlet conduit, reciprocable means spaced therefrom for sealing off a portion of said tubular member from said discharge conduit, reciprocable means engaging said tubular member to alternately decrease and increase the capacity thereof between said sealing means, driven means for reciprocating said means in relative succession to move a fluid from said inlet conduit to said discharge conduit through said flexible tubular member, and means for adjusting the amplitude of movement of said reciprocable capacity varying means.

2. In a pump of the character described, a flexible tubular member, an inlet conduit leading into one end thereof, a discharge conduit leading from the other end thereof, means for sealing off a portion of said tubular member from said inlet conduit, means spaced therefrom for sealing off a portion of said tubular member from said discharge conduit, reciprocable means engaging said tubular member to alternately decrease and

increase the capacity thereof between said sealing means, means controlling the length of stroke of said reciprocable means, and driven means for operating said sealing means and said capacity varying means in relative succession to move a fluid from said inlet conduit to said discharge conduit through said flexible tubular member.

3. In a pump of the character described, a body portion having a continuous passage of substantially uniform cross section therein, a flexible tubular member, an inlet conduit leading into one end thereof, a discharge conduit leading from the other end thereof, means cooperating with the wall of said passage to deform a predetermined portion of said tubular member to reduce the capacity of said portion thereof, means at a predetermined station between said inlet conduit end of said tubular member and said deforming means cooperating with the wall of said passage to seal said member at said station, means at a predetermined station between said other end of said tubular member and said deforming means cooperating with the wall of said passage to seal said member at said last mentioned station, means for moving said deforming means and said sealing means toward and away from said wall in relative succession to move a fluid from said inlet conduit to said discharge conduit through said tubular member, and means for limiting the amplitude of movement of said deforming means.

4. In a pump of the character described, a body portion having a passage therethrough, a flexible tubular member having an unobstructed passage therethrough mounted in said passage, an inlet connection leading into one end of said tubular member, a discharge connection leading out of the other end thereof, a plurality of followers mounted for reciprocation in said body portion each engaging said tubular member at one end thereof, a shaft, and a single cam on said shaft engaging said followers to successively move the same into engagement with said tubular member to move a fluid through the same from said inlet connection to said discharge connection.

5. In a pump of the character described, a body portion having a passage therethrough, a flexible tubular member mounted in said passage, an inlet connection leading into one end of said tubular member, a discharge connection leading out of the other end thereof, a plurality of followers mounted for reciprocation in said body portion transversely of said passage each engaging said tubular member to squeeze the same between said followers and the wall of said passage, rotatable means engaging said followers to move the same into squeezing engagement with said tubular member, and adjustable means for limiting the reciprocating movement of one of said followers.

6. In a pump of the character described, a body portion having a continuous passage of substantially uniform cross section therethrough, a flexible tubular member mounted in said passage, an inlet connection leading into one end of said tubular member, a discharge connection leading out of the other end thereof, an inlet valve comprising a blunt ended follower mounted for reciprocation in said body portion transversely of said passage to engage the blunt end thereof with said tubular member, an outlet valve comprising a blunt ended follower mounted for reciprocation in said body portion transversely of said passage to engage the blunt end thereof with said tubular member in spaced relation to said

inlet valve follower, a wide, flat faced reciprocable member mounted to engage said tubular member between said followers to vary the capacity of the portion of said tubular member engaged thereby, and means for reciprocating said followers to squeeze said tubular member between the same and wall portions of said passage to seal said tubular member and said reciprocable member to alternately decrease and increase the capacity of said portion of said tubular member in such order as to pump a fluid through said tubular member from said inlet connection to said discharge connection.

7. In a pump of the character described, a body portion having a passage therein, a flexible tubular member mounted in said passage, an inlet at one end thereof, an outlet at the other end thereof, reciprocable means for sealing off a portion of said tubular member from said inlet, reciprocable means spaced therefrom for sealing off a portion of said tubular member from said outlet, reciprocable means engaging said tubular member to alternately decrease and increase the capacity thereof between said sealing means, and driven means for reciprocating said means in relative succession to move a fluid from said inlet to said outlet through said flexible tubular member, said tubular member being normally of substantially circular cross section and said passage being of greater cross sectional dimension than the normal diameter of said tubular member transversely of the direction of reciprocation of said means, and of substantially the cross section of said tubular member in the direction of reciprocation of said means.

8. In a pump of the character described a flexible walled pump chamber, flexible walled inlet valve means, flexible walled discharge valve means, means for squeezing the flexible walls thereof in such relative order as to draw fluid into said pump through said inlet valve means and discharge it through said discharge valve means, and means for adjusting the stroke of one of said squeezing means to control the quantity of fluid passing through said pump during one cycle of operation thereof.

9. In a pump of the character described, a flexible tubular member of a predetermined normal cross sectional shape having a uniform passage of a defined normal cross sectional area therethrough free of obstructions therein, a housing through which said tubular member extends, inlet valve means and outlet valve means engaging said tubular member at spaced points in said housing to control flow of fluid therethrough, a member reciprocable in said housing having a blunt end engaging said tubular member between said inlet valve means and said outlet valve means to alternately decrease and increase the capacity of the portion thereof between said valve means, and driven means for operating said valve means and said member in such relative succession that fluid enters said portion of said tubular member through said inlet valve means and is discharged through said outlet valve means, said means positively moving said reciprocable member in capacity decreasing direction, said tubular member having the inherent tendency to return to normal cross sectional shape upon deformation thereof to move said reciprocable member in capacity increasing direction.

10. In a pump of the character described, a flexible tubular member of a predetermined nor-

mal cross sectional shape having an unobstructed passage of a defined normal cross sectional area therethrough, inlet valve means and outlet valve means engaging said tubular member at spaced points to control flow of fluid therethrough, a reciprocable member engaging said tubular member between said inlet valve means and said outlet valve means to alternately decrease and increase the capacity of the portion thereof between said valve means, driven means for operating said valve means and said member in such relative succession that fluid enters said portion of said tubular member through said inlet valve means and is discharged through said outlet valve means, and means for adjusting the stroke of said reciprocable member.

11. In a pump of the character described, a body portion having a continuous passage of substantially uniform cross section therethrough free of obstructions therein, a flexible tubular member mounted in said passage, said tubular member having the inherent tendency to resume its normal cross sectional shape upon distortion thereof, a plurality of followers mounted for reciprocation in said body portion each engaging said tubular member at one end thereof to squeeze the same solely between itself and a wall portion of said passage, a shaft, and cam means on said shaft engaging the other ends of said followers to successively positively move the same into squeezing engagement with said tubular member and to permit movement of said followers in a return direction due to the tendency of said tubular member to return to its normal shape to move a fluid through the same in a predetermined direction.

12. In a pump of the character described a body portion having a shaft mounted therein, a single cam on said shaft, said body portion having a continuous passage extending around said cam in spaced relation thereto and having spaced end portions, a flexible tubular member mounted in said passage with the ends thereof projecting from said body portion at the ends of said passage, and means actuated by said cam reciprocable in said body portion and engaging said tubular member to successively squeeze the walls of the same together between said reciprocable means and a wall of said passage, said reciprocable means comprising inlet and discharge valve means spaced along said passage and a member that alternately decreases and increases the capacity of said tubular member between said valve means having a blunt end engaging said tubular member.

13. In a pump of the character described a body portion having a shaft mounted therein, a single cam on said shaft, said body portion having a continuous passage extending around said cam in spaced relation thereto and having spaced end portions, a flexible tubular member mounted in said passage with the ends thereof projecting from said body portion at the ends of said passage, means actuated by said cam reciprocable in said body portion and engaging said tubular member to successively squeeze the walls of the same together between said reciprocable means and a wall of said passage, said reciprocable means comprising inlet and discharge valve means spaced along said passage and a member that alternately decreases and increases the capacity of said tubular member between said valve means having a blunt end engaging said tubular member, and means for adjusting the stroke of said capacity varying reciprocable member.

14. In a pump of the character described, a flexible tubular member of a predetermined normal cross sectional shape having an unobstructed passage of a defined normal uniform cross sectional area therethrough, a housing through which said tubular member extends, inlet valve means and outlet valve means engaging said tubular member at spaced points in said housing to control flow of fluid therethrough, a member reciprocable in said housing having a blunt end engaging said tubular member between said inlet valve means and said outlet valve means to alternately decrease and increase the capacity of the portion thereof between said valve means, and a single cam for operating said valve means and said member in such relative succession that fluid enters said portion of said tubular member through said inlet valve means and is discharged through said outlet valve means without inflating said portion and without increasing the cross sectional area of the passage therethrough beyond normal.

15. In a pump of the character described a body portion having a shaft mounted therein, a single cam on said shaft, said body portion having a continuous passage extending around said cam in spaced relation thereto, a flexible tubular member mounted in said passage, and means actuated by said cam reciprocable in said body portion and engaging said tubular member to

successively squeeze the walls of the same together between said reciprocable means and a wall of said passage, said reciprocable means comprising inlet and discharge valve means spaced along said passage and a member that alternately decreases and increases the capacity of said tubular member between said valve means having an end engaging said tubular member.

16. In a pump of the character described a body portion having a passage therethrough having a continuous rigid fixed wall restrained against any movement, a flexible tubular member mounted in said passage, said tubular member having an unobstructed passage of uniform cross section therein and having an inherent tendency to return to its normal contour upon deflection thereof, a plurality of followers mounted for reciprocation in said body portion transversely of said passage each engaging said tubular member to squeeze the same solely between said followers and the fixed wall of said passage that is restrained from any movement, and rotatable means engaging said followers to move the same into squeezing engagement with said tubular member and release the same to permit said tubular member to return the same under the influence of its tendency to return to normal.
